SCOOTER SKI

Ralph R. Hylan, Lexington, Mass.

Application June 5, 1940, Serial No. 338,979

1 Claim. (Cl. 280—23)

My present invention relates to scooters and more particularly to ski scooters for use on snow and ice, the ski runners being specially designed, the forward runner being pivoted.

The principal object of my invention comprises an improved scooter ski;

Another object is an improved scooter ski runner for use on snow;

Still another object is an improved scooter ski runner skate member which is horizontally adjustable on the ski runner;

And still another object is an improved scooter ski runner skate member which is removable, and

Other objects and novel features comprising the construction and operation of my invention will be apparent as the description of the same progresses.

In the drawing illustrating the preferred embodiment of my invention:

Fig. 1 is a side elevation of the scooter ski with the ice skate members attached, the dot-and-dash lines indicating adjustable positions of the ice skate member on the rear ski runner member;

Fig. 2 is a top plan cross-section of the device taken on the line 2—2 of Fig. 1;

Fig. 3 is a bottom plan view of the scooter ski, the ice skate members being removed;

Fig. 4 is a cross-section taken on the line 4—4 of Fig. 1, portions being shown in elevation and other portions being broken out for convenience;

Fig. 5 is an enlarged cross-section taken on the line 5—5 of Fig. 1;

Fig. 6 is a top plan view of the rear ice skate member;

Fig. 7 is a side elevation of the rear ice skate member removed from the ski runner;

Fig. 8 is an enlarged perspective view of the hinge block member which is mounted in the steering post, and

Fig. 9 is a side elevation of the ice skate member used on the front ski runner.

Referring more in detail to the drawing, 10 indicates the rear ski runner, and 11 indicates the front ski runner. Preferably both the front and rear ski runners are constructed from wood or other light weight material.

On the upper surface of the front runner 11 I have provided a hinge plate member 12 having vertically extended hinge members 13. A steering post member, generally indicated at 14, and more specifically composed of two flat members 15, is provided. The lower portion of the steering post member is expanded to form a fork the lower ends of which are pivoted in the hinge portions 13 of the hinge plate member 12 by means

of the pin 16, the two ends of the fork being separated by the sleeve spacer member 17 which surrounds the central portion of the pin 16.

In the upper portion of the steering post fork 5 is located the hinge block 18, better shown in Fig. 8. The hinge block 18 is securely mounted between the inside surfaces of the fork by means of rivets or bolts 19 which pass through the holes 20 in the block. The rear side of the hinge block 18 is extended beyond the steering post fork and is provided with a substantially vertical bore 40. The top of the steering post 14 is provided with the steering handle 21 which is affixed to right angle portions of the steering post members 15 by means of the bolts 22. The upper portion of the members 15 may be solidly fixed together, as by rivets 23 or by any other suitable means such as welding.

On the forward end of the ski runner 10 is mounted by means of the rivets 24 a hinge plate member 25. The front end of the hinge plate member 25 is split at 26 to form two hinge portions 27 and 28. These hinge portions 27 and 28 are twisted toward each other and the outer ends 25 of each are curved to form loops 27a and 28a which fit over the top and bottom faces of the hinge block 18 adjacent the bore 40. A hinge pin 29 passes through the loops 27a and 28a and the bore 21 in the hinge block 18 and completes the hinge assembly between the steering post 14 and the rear ski runner hinge plate 25.

It will thus be seen that when the steering post 14 is turned the front ski runner 11 will pivot on the hinge pin 29 and at the same time the front runner will pivot on its hinge connecting the lower ends of the fork of the steering post. When the front runner is turned, as above described both the front and rear runners will tilt at an angle.

When the scooter ski is used on the snow the bottom of the runners 10 and 11 are as shown in Fig. 3 in which the central portion 30 and 31 of the runners 10 and 11 respectively are recessed leaving the high side edges 30a and 31a. These recessed areas 30 and 31 perform two separate functions. When the scooter is used on the snow the high portions 30a and 31a prevent the runners 10 and 11 from skidding sideways, and when the scooter is used on ice they form a part of the slide ways for the ice skates 32 and 33.

It will be observed that the runner 10 is provided with a plurality of holes 34 and the rear ice skate member 32 is provided with a like series of holes 35 passing through the top flanges of the member 32. The vertical portion 35 of the ice member contacts with the ice and be-

cause of the fact that the member 32 may be adjusted toward the front or rear of the runner 10 it is possible to position the ice skate member in the proper position to suit different conditions of use by different sized people. Some people who are short and have a shorter reach would stand nearer the forward portion of the runner 10 thereby depressing the runner too much in front of the skate member 32 but by moving the member 32 forward such condition is corrected. It will be seen from Fig. 5 that the top of the ice skate member 32 is flat and has approximately the same thickness as the depth of the slide ways 30 and 31.

The front ice skate member 33 has a top portion which is curved to fit the recessed portion 31 which blends into the curved under side of the runner toward its top. This front ice member 33 is removable but not adjustable being mounted to the runner 11 through the holes 37, in the same manner as in the case of the rear runner 10 and ice skate member 32.

When used as an ice scooter the bottom surface of the runners 10 and 11 are raised above the ice, and the adjustable feature makes it possible to adjust the rear ice member 32 forward or back, as the case may be, so that the center of gravity

of the user is in the proper place thus preventing the more flexible forward portion of the runner 10 from bending down and engaging the ice.

When the ice members 32 and 33 are removed the slide ways on the bottom of the runners 10 and 11 provide guiding means to prevent the ski runners from slipping sideways or skidding on curves or slopes.

It is to be understood that I may vary the shape and proportions of the various parts to suit various conditions in manufacture, etc., within wide limits without departing from the spirit of the invention.

Having thus described my invention, what I claim as new is:

An improved scooter ski comprising in combination a front and rear runner, a steering post pivoted to said rear runner, a rectangular slide-way recess extending all of the way along the lower surface of said rear runner, a T-shaped skate member located in said recess having the flat top face of the T shape located in said recess slideway, said skate member being longitudinally adjustable in said slide way recess.

RALPH R. HYLAN.
